UNITED STATES PATENT OFFICE.

GABRIEL ALBERT VALENTIN SOULACROIX, OF PARIS, FRANCE.

BUCKLE FOR STRAPS, BELTS, AND THE LIKE.

1,380,261.

Specification of Letters Patent. Patented May 31, 1921.

Application filed August 7, 1918. Serial No. 248,783.

To all whom it may concern:

Be it known that I, GABRIEL ALBERT VALENTIN SOULACROIX, a citizen of the Republic of France, and a resident of 12 Avenue de la Grande Armée, Paris, France, have invented new and useful Improvements in Buckles for Straps, Belts, and the like, of which the following is a specification.

The present invention relates to an improvement in buckles for straps, belts, girths and the like, of the type in which the tongue of the buckle is mounted on a chassis pivoted on the rear part of the buckle frame, so that by turning this chassis about its pivot the point or free extremity of the tongue can be pulled back or withdrawn until it escapes from the front cross bar of the buckle and the strap be easily freed by means of a pull exerted thereon.

In accordance with the present invention, one or more springs supported upon the pivotal axis of the chassis carrying the tongue or prong upon the buckle, acts or act upon this chassis for the purpose of maintaining it normally applied against the buckle frame—that is to say with a view to holding the tongue in engagement with one of the holes of the strap, belt or the like, so that it is necessary to overcome the tension of the spring or springs in order to be able to open the buckle by turning the chassis about the buckle.

The annexed drawing shows in elevation one form of carrying out the invention.

The buckle frame comprises a transverse bar or spindle a^4 connecting the parallel longitudinal arms a' between the rear and front cross-bars a and a^2 . Upon the rear cross-bar a is stitched or secured in the known manner, one of the ends of the strap, belt or the like c . Upon the front cross-bar a^2 covered by a metal sleeve a^3 , there rests the point or free end of the tongue or prong d ; this latter is jointed or pivoted upon a cross-bar b^2 connecting the two sides or parallel longitudinal arms b of the prong chassis. These two arms b are pivoted at b' upon the transverse spindle a^4 of the buckle frame. A spring e supported or bearing on

the pivotal spindle a^4 of the frame b b' b^2 50 and acting upon the cross-bar b^2 which carries the tongue d , maintains the chassis applied normally against the buckle frame by means of curved lateral claws b^4 resting on the arms a' of the buckle. The tongue d is 55 consequently held forcibly in the hole of the strap, belt or the like with which it is engaged, and the buckle is kept closed. In order to open the buckle it is necessary to overcome the tension of this spring e in order 60 to be able to turn the chassis b b' b^2 about its pivotal axis a^4 on the buckle. When this action takes place, in the known manner, from the exterior upon the lateral claws b^4 , the point of the tongue d slipping upon 65 the front cross-bar a^2 of the buckle, is pulled back and escapes from this cross-bar. It is then sufficient to exert a light pull upon the free end of the strap or the like to free the latter from the buckle. 70

Naturally, various detail modifications in the example represented can be made without departing from what I claim as my invention.

I claim—

A buckle comprising a frame having longitudinally spaced cross bars, to one of which a strap end is adapted to be permanently secured, and beneath the other of which the free end of the strap is adapted to be passed 80 up between the sides of the frame, a chassis pivoted to said frame at a point located between said cross bars, a tongue on said chassis adapted to pass through said free end of the strap and to overlie the cross bar beneath which the free end of the strap is passed, in combination with spring means 85 engaging said chassis and tending to maintain the tongue in position to overlie said cross bar in strap-engaging position, substantially as described. 90

In testimony whereof I have signed my name to this specification.

GABRIEL ALBERT VALENTIN SOULACROIX.
